UNITED STATES PATENT OFFICE

2,647,203

LIGHT REFLECTOR

Harold E. Smith, Lykens, Pa.

Application August 2, 1950, Serial No. 177,173

18 Claims. (Cl. 240—41.1)

1 This invention relates generally to light reflectors and more particularly to an improved ovoidal reflector of the type disclosed in Patent Number 1,913,518, issued to myself and Harry E. Buffington, jointly, on June 13, 1933.

The ovoidal reflectors disclosed in the above-mentioned patent and those used in the multiple light projector or headlamp disclosed in my co-pending application, Serial Number 169,869, filed June 23, 1950, now Patent No. 2,592,075, may be formed by use of an elliptical directrix in a directrix plane and a series of generating ellipses. The generating ellipses are normal to the directrix plane and diminish in size as they move away from the major axis of the directrix ellipse. One vertex of the generating ellipse is locused in the directrix ellipse and the remote focus of the generatrix is locused on a curved line (Patent Number 1,913,518) or a straight line (application Serial Number 169,869).

In the former instance the reflected light rays all pass through the curved line locus. Consequently the ultimate reflector and baffle plate trimming edge used with the reflector must also be curved to correspond therewith or a loss of efficiency will result. The use of a curved baffle and ultimate reflector requires more critical adjustment to prevent light from leaving the ultimate reflector and headlamp in upward directions. In the latter instance all of the light rays from the reflector focal point are not reflected through the straight line locus but some pass slightly to one side or the other thereof. When this reflector is combined with an ultimate cylindrical parabolic reflector as described, the rays not passing through the remote focal line are reflected downwardly by the ultimate reflector or trimmed by the baffle and represent a reduction in intensity of the horizontally projected portion of the projector beam.

It is a general object of this invention to provide an improved, ovoidal reflector which overcomes the disadvantages of known reflectors as outlined above.

A more particular object of the invention lies in the provision of an ovoidal reflector having elliptical directrices and capable of reflecting all light from a focal point in converging directions through a straight line remote focus.

Another object lies in the provision of an ovoidal reflector having an elliptical directrix and an elliptical generating ellipse of varying size such that all light from a focal point will be converged through a focal line thereby enabling more efficient concentration of light into a beam of parallel rays when the reflector is combined with an

ultimate parabolic reflector having a focal line, and reducing the loss of light when combined with a baffle having a straight line light trimming edge.

Still another object of the invention lies in the provision of an ovoidal reflector capable of reflecting all light from a point source through a straight line remote focus in converging directions, whose angle of convergence may be varied by selection of proper elliptical directrices so that the lateral divergence of the reflected light beam may be controlled.

A further object of the invention lies in the provision of a reflector capable of reflecting light from a source at its focal point through a remote focal straight line which is obliquely angled with respect to the primary axis of the reflector so that the lateral or horizontal direction of a light beam reflected therefrom may be controlled by selection of an appropriate oblique angle for said remote focal line.

A still further object of the invention lies in the provision of a reflector having a proximate focal point and a remote focal straight line and adapted to reflect all focal rays from said point through said focal straight line, the direction of the reflected beam being controllable by selection of an appropriate angle for the focal line with respect to the primary axis of the reflector, and the spread of the reflected beam being controllable by the selection of an appropriately sized conic section curve as a directrix in the plane which includes the focal line.

I achieve these objects and such other additional objects, features and advantages as may hereinafter appear or be pointed out, in the manner illustrated by several embodiments shown in the appended drawings, wherein:

Figure 1 is a front elevation of a reflector in accordance with the invention.

Figure 2 is a cross-section taken along line 2—2 of Fig. 1.

Figure 3 is a perspective view of the reflector.

Figure 4 is a diagrammatic front elevation illustrating the paths of rays reflected in the plane of the rear boundary edges of the reflector.

Figure 5 is a diagrammatic view showing the paths of rays reflected in the plane corresponding to that of Fig. 2 and normal to the plane depicted in Fig. 4.

Figure 6 is a diagrammatic central section of a headlamp including the reflector of the invention disposed substantially horizontally and illustrating one typical application thereof.

Figure 7 is a diagrammatic top plan view of the headlamp of Fig. 6.

Figure 8 is a view similar to Figure 6 of an

3

other headlamp in which the reflector is vertically disposed and illustrating another and preferred mode of use.

Figure 9 is a diagrammatic top plan view of the headlamp of Fig. 8.

Figure 10 is a diagram illustrating a mode of generating the reflector surface and represents the directrix ellipse in the central bisecting plane of the reflector corresponding to Fig. 2 with portions of the directrix ellipses which fall in a plane normal to the first named plane rotated into said plane for illustrative purpose.

Figures 11 and 12 are views of the reflector respectively similar to those of Figs. 1 and 3 and showing certain of the surface generating ellipses.

Figure 13 is a front elevation similar to Fig. 11 of a modified reflector utilizing surface generating parabolas.

Figure 14 is a diagram illustrating preliminary steps in another method of generating the reflector surface.

Figure 15 is a diagram illustrating additional preliminary steps in generating the reflector surface.

Figure 16 is a perspective view of a reflector having an oblique remote focal line and showing certain of the surface generating ellipses obtained by the method illustrated in Figs. 14 and 15.

Figure 17 is a diagrammatic elevational view of separate reflectors having normal and oblique remote focal lines combined in one possible manner to correlate and control the composite reflected beam.

My improved reflector 10 in one of its preferred embodiments is shown in Figs. 1 to 3 to be a warped surface of double curvature, generally ovoidal in shape and having a central bisecting section which is an ellipse 11 whose foci are located at 12 and 13. The rear boundary edges of the reflector as viewed in Fig. 1 are also ellipses identified as 15 and 20 which fall in a plane including the points 12 and 13 and normal to the bisecting plane of ellipse 11.

Referring to Figs. 10 to 12, where is shown the method of generating the reflector warped surface connecting ellipses 11, 15 and 20, it will be noted in Fig. 10 that the curves 15 and 20 have been rotated into the plane of ellipse 11 for purpose of clarifying the mode of fabrication. In forming the surface, a directrix ellipse 11 with foci 12 and 13 is selected. Directrix ellipse 15 is then chosen in a plane including points 12 and 13 but at right angle to the plane of ellipse 11. A common point 12 is used as a focus for both ellipses 11 and 15, the second focus 16 of ellipse 15 being selected in such manner as to produce the desired lateral convergence of the reflected light. An ordinate for ellipse 15 is then drawn through 13 at right angle to line 12-13. This ordinate intersects ellipse 15 at points 17 and 18, one half of this ordinate being shown in Fig. 10 at line 13-18. A second directrix ellipse 20 is then drawn in the plane of ellipse 15, passing through end points 17, 18 of the ordinate and having its vertex coincident with the vertex of ellipse 11. The points 12 and 21 are the foci of ellipse 20 and point 21 will generally fall on the same side of ordinate 17, 18 as point 12 at a distance from point 13 equal to distance 13-16. Now the surface connecting ellipses 11, 15 and 20 is generated by an infinite series of ellipses of varying size, certain of which are indicated by the numerals 31 through 47. Each of these ellipses lie in planes making successively larger angles with the plane of ellipse 15, which in Fig. 10 is represented by line 21, 12,

4

13 and 16. Each ellipse has its vertex lying on ellipse 11 and passes through points 17 and 18. In effect, therefore, the reflector surface is generated by rotation of an ellipse of varying size about axis 17-18, the vertex of the generating ellipse being located on directrix 11, the generating ellipse retaining a common ordinate on the axis and defined by end points 17 and 18, and the foci of the generating ellipse drawing closer together as the ellipse is rotated being located on curves 50 and 51 and moving in the direction of the arrows in Fig. 10. For example, the foci of ellipse 32 would fall at points 52 and 53 while the foci of ellipse 43 would fall at points 54 and 55.

When formed in the described manner, reflector 10 will reflect all light rays from focal point 12 through ordinate line 17-18 by reason of the directrix ellipse 11 warping the surface in one dimension. This action is diagrammatically illustrated in Fig. 5 for the light rays in the plane of ellipse 11. Rays striking portions of surface 10 displaced laterally from ellipse 11 are reflected along the planes of the generating ellipses which pass through the points of impingement and include the ordinate 17-18. Hence these rays also pass through ordinate 17-18. Laterally, all rays from focal point 12 are converged toward circular arc 51 of Fig. 10 and such rays in the plane of the directrix ellipses are illustrated in Fig. 4 as being converged toward foci 16 and 21. Rays striking the surface 10 outside of this plane are reflected toward the arc 51 which includes the traveling foci such as 16, 53, 55 and 21 except in that a slight reduction in convergence of light rays is obtained due to the displacement of the second foci along path 50. It is therefore apparent that the reflector though formed with elliptical directrices in two dimensions nevertheless provides a straight line as a remote focal line.

It will be apparent from the above that the reflector surface may be considered as generated by the revolution about a fixed axis defined by end points 17 and 18 of a conic section curve, varying in size as it revolves and having a directrix ellipse in a bisecting plane normal to the axis as the locus of the vertex of the generating curve, the generatrix curve retaining the axis with its end points as a common ordinate. Conic section curves other than ellipses may be utilized as the varying generatrix. One example is illustrated in Fig. 13 wherein the reflector surface 10' is formed by the revolution of a varying parabola 70-71 which at intermediate stages of revolution is shown as parabolas in different planes and of differing size referenced 32', 34', 36', etc., corresponding to the generating ellipses of similar number shown in Figures 10-12. Reflector surfaces so formed by rotation of conic section curves other than ellipses will modify the obtained lateral spread of the reflected beam but still reflect all focal rays through the common ordinate 17'-18'.

Referring now to Figures 14-16, there is shown another method of forming the improved reflector, the illustration being directed to a reflector having a remote focal line which is oblique to the primary axis of the directrix ellipse. A directrix ellipse 15' is selected having foci 12' and 16'. A remote focal line 17'-18' is then drawn in the directrix plane at any desired angle to the primary axis 12'-16' and intersecting the latter at 13'. For each focal ray r , from focal point 12', an ellipsoid is drawn having foci at 12' and 75 (Fig. 14) and which is tangent to the

directrix 15 at its intersection 16 with line 18-18'. The ellipsoid thus formed is shown in Fig. 14 as an ellipse 37 representing the intersection of the ellipsoid with the directrix plane. A plurality of segments of these ellipsoids are shown in Fig. 15 referenced 80 through 90, and these segments extend from the point of tangency of the ellipsoid with the directrix ellipse to the intersection 77 with line 16, 75, 16' for each ellipsoid. Each ellipsoid is intersected by a plane 10 vertical to the directrix plane and including the directrix focus 16' and the intersection 75 of the ellipsoid axis with the selected focal line 17'-18'. The intersections of these vertical, converging planes with their corresponding ellipsoids are each a vertically positioned ellipse. One of these designated 97 in Fig. 14 has been rotated into the directrix plane for clarity. These intersections or generatrix ellipses when formed for an infinite series of ellipsoids comprise the reflector surface 100, which is shown in perspective in Fig. 16 with certain of the generatrix ellipses 91 through 99 indicated in dotted lines. It will be observed from the example in Fig. 14, that the generatrix ellipses each have a vertex 76 (the point of ellipsoid tangency) on the directrix ellipse and the other vertex at 77 (the intersection of the vertical plane with the ellipsoid). One focal point is located at 75 (the intersection of the ray with the selected focal line and the other focal point 18 is spaced inwardly from the directrix ellipse a distance equal to the distance from focus 15 to vertex 77. The lower boundary 20' of reflector 100 lying in the directrix plane includes all of the vertices 77.

It is apparent that each of the ellipsoids 80-90 would direct all reflected rays from focal point 12' to its respective axis intersection with line 17'-18' as shown at 75 in Fig. 14. The vertical sections of the ellipsoids 91-99 must therefore also direct all reflected rays to this line. Since the reflector 100 is formed of an infinite number of such sections it will necessarily reflect all rays received from focus 12' through remote focal line 17'-18' in directions converging toward 16'.

It will be observed from the above that reflector surface 100 will be identical with reflector surface 10 of Figs. 1, 2 and 12 if 15' is selected equal in size to 15 and remote focal line 17'-18' is selected at right angles to the primary axis intersecting the latter at point 18 even though generated in a different manner.

To illustrate the application of my improved reflector, reference will be made to Figs. 6 to 9 wherein such reflectors are shown diagrammatically as combined with a cylindrical parabolic reflector and a baffle plate having a light trimming edge. In Figs. 6 and 7 the reflector 10 is substantially horizontally disposed, making only a small angle therewith, and its focal line 17-18 coincides with the straight focal line of cylindrical parabolic reflector 60. It is also desirable to utilize a baffle plate 61 having a light trimming edge substantially coincident with line 17-18 so as to prevent any rays from striking the ultimate reflector from a position in front of its focal line and thereby eliminate upwardly directed reflections therefrom. This application of the reflector is similar to that described in Patent Number 1,913,518, referred to above, but provides the advantages of concentrating more of the light from the source in the beam of parallel rays emerging from the headlamp because of the straight focal line obtained with reflector 10. The reflector also reduces the light 75

losses due to trimming by the baffle plate edges, and further is advantageous in simplifying the structure of the ultimate reflector and headlamp thereby reducing cost of fabrication.

Figs. 8 and 9 illustrate a mode of utilizing the improved reflector disposed vertically and paired similar to the use disclosed in my copending application Ser. No. 169,869, referred to above. In such application one of the two reflectors is preferably cut off in the horizontal level of its remote focal line which coincides with generating ellipse 39 of Fig. 10 and it is at this level that it meets the parabolic, cylindrical reflector 62. The other reflector 10 is cut off at a higher level where it is connected to or merged with baffle plate 63 which has a straight line light trimming edge substantially coincident with the focal lines of both ovoidal reflectors and the ultimate reflector 62. In this application reflectors 10 provide better control of the lateral divergence of the final light beam by the use of elliptical directrices and at the same time increase the beam intensity and headlamp efficiency by concentrating the reflected light from the ovoids into a straight line.

Fig. 17 illustrates a mode of utilizing a plurality of reflectors disposed vertically and paired in a manner similar to that disclosed in my copending application Ser. No. 169,869. Here a pair of reflectors 10 (one not shown) back to back, are located centrally of a composite projector having multiple light sources. On either side, pairs of reflectors 100, also back to back, are mounted with their remote focal lines aligned with and forming continuations of the focal line 17-18 of the center reflectors. An ultimate parabolic cylindrical reflector (not shown) similar to 62, Fig. 8 is provided whose focal line coincides with the remote focal lines of reflectors 10 and 100. The light beams reflected by the center reflectors 10 will be re-reflected by the ultimate reflector and projected in a forward direction. The beams reflected by the outside reflectors 100 are angled toward the center and will be re-reflected by the ultimate reflector laterally so as to cross the center reflector beam.

In actual headlight practice the angle selected for the remote focal line will be in the order of 2-3 degrees from normal to the primary axis rather than the larger angle illustrated for clarity. A small angle will cross the beams at approximately 300-400 feet in front of the headlamp.

It will be observed that the selection of suitable elliptical directrices in my improved reflector provides control of horizontal or lateral beam divergence, while selection of a remote focal line suitably angled with respect to the primary axis of the reflector provides control of the direction of beam emission. The existence of both types of control in one reflector provides great flexibility of design and use.

It will be apparent that my improved reflector may be used in different angular dispositions than those illustrated and in conjunction with other reflectors than those shown. It is in fact useful whenever it is desired to collect light from a source and converge it through a straight focal line. Various modifications in form and detail will suggest themselves to those skilled in the art, without necessarily departing from the spirit and the scope of the appended claims.

Having thus described my invention, what I claim as new and desire to secure by Letters Patent is:

1. A light reflector comprising, an ovoidal sur-

face having a proximate focus which is a point and a remote focus which is a straight line, said surface being composed of an infinite series of ellipses all having a common ordinate which is coincident with said remote focal line and lying in planes which make successively larger angles with a directrix plane containing the remote and proximate foci.

2. A light reflector comprising an ovoidal surface having a point focus and a straight focal line spaced apart in a directrix plane, a pair of elliptical directrices in said plane and having a common ordinate coinciding with said focal line, a third directrix ellipse having one focus on said focal line and the other focus coinciding with the point focus of the surface, said third ellipse lying in a plane at right angles to said directrix plane, said ovoidal surface being formed to include the three directrix ellipses by a series of ellipses of varying size each lying in planes swung about said focal line so as to make successively larger angles with said directrix plane and each ellipse having a vertex lying in said third directrix ellipse and a common ordinate coinciding with the common ordinate of said pair of elliptical directrices.

3. A light reflector comprising, an ovoidal surface, having a directrix ellipse lying in a directrix plane, said directrix ellipse having a proximate focus coincident with that of the reflector and a primary axis, said surface being formed by a series of generating ellipses which are intersections of planes, vertical to said directrix plane and converging to the remote focus of said directrix ellipse, with a series of ellipsoids all having a common focus coincident with the proximate focus of the directrix ellipse and remote foci lying on a straight line in the directrix plane oblique to the directrix primary axis, said ellipsoids being each tangent to the directrix ellipse at the intersection of the vertical plane which includes its remote focus with the directrix ellipse, whereby the ovoidal surface is characterized by a proximate focal point coincident with that of the directrix ellipse and a remote focal line coincident with the said straight line oblique to the primary axis of the directrix ellipse.

4. A light reflector comprising an ovoidal surface curved in two dimensions so as to provide a proximate focal point and a remote focal straight line, said surface being characterized by an elliptical directrix in a directrix plane and having a proximate focus coincident with the focal point of the reflector surface, a remote focus and a primary axis connecting the directrix foci, a directrix straight line intersecting said primary axis, a series of ellipsoids all having proximate foci coincident with the proximate focus of the directrix ellipse and remote foci lying in said directrix straight line, said ellipsoids being tangent to said directrix ellipse, said surface being generated by a series of varying ellipses said surface generating ellipses being intersections with said ellipsoids of a series of planes vertical to said directrix plane, all including the remote focus of the directrix ellipse, and each intersecting the directrix ellipse at the point of tangency of its corresponding ellipsoid.

5. A light reflector as set forth in claim 4 wherein said straight line directrix is inclined at an oblique angle to said primary axis of the elliptical directrix.

6. A light reflector comprising an ovoidal surface having a proximate focal point and a remote focal straight line spaced apart in a directrix

plane, an elliptical directrix in said plane having a focus coincident with said proximate focal point and a remote focal point lying on a primary axis, said ovoidal surface being formed to include a series of generating ellipses of varying size, each lying in a plane vertical to the directrix plane and converging toward the remote focus of the directrix ellipse, said generating ellipses each having a vertex lying in the directrix ellipse and a remote focus lying in the said remote focal straight line, the proximate focus of each generating ellipse falling within the directrix ellipse and in the directrix plane a distance equal to the distance between its remote focus and its remote apex.

7. A light reflector as set forth in claim 6 wherein said remote focal straight line lies in said directrix plane inclined at an oblique angle to said primary axis of the elliptical directrix.

8. A light reflector comprising an ovoidal surface having a proximate focal point, a selectively angled remote straight line focus, and a selected directrix, all in the directrix plane, said ovoidal surface being generated by a series of ellipses in planes perpendicular to said directrix plane and said perpendicular planes extending along the paths of focal rays of the directrix.

9. A light reflector comprising an ovoidal surface having a proximate focal point, a selectively angled remote straight line focus, and a selected directrix, all in the directrix plane, said ovoidal surface being generated by a series of ellipses in planes perpendicular to said directrix plane and said perpendicular planes extending along the paths of focal rays of the directrix, said generating ellipses each having its proximate apex located in the directrix and its remote focus located in said selectively angled remote straight focal line.

10. A light reflector comprising an ovoidal surface having a proximate focal point, a selectively angled remote straight line focus, and a selected directrix, all in the directrix plane, said ovoidal surface being generated by a series of ellipses in planes perpendicular to said directrix plane and said perpendicular planes extending along the paths of focal rays of the directrix, said generating ellipses each having its proximate apex located in the directrix and its remote focus located in said selectively angled remote straight focal line, the proximate focus of each generating ellipse being located within the directrix by a distance equal to that by which its remote apex extends beyond said selectively angled straight remote focal line in the plane of the directrix and on the major axis of the generating ellipse.

11. In combination, a parabolic cylindrical reflector having a straight focal line, and an ovoidal reflector having a proximate focal point, a selectively angled remote straight line focus which coincides with the focal line of the parabolic reflector, and a selected directrix, all in the directrix plane, said ovoidal reflector being generated by a series of ellipses in planes perpendicular to said directrix plane, and said perpendicular planes extending along the paths of focal rays of the directrix.

12. The structure of claim 11, said generating ellipses each having its proximate apex located in the directrix and its remote focus located in said selectively angled remote straight line focus.

13. The structure of claim 12, the proximate focus of each generating ellipse being located within the directrix by a distance equal to that by which its remote apex extends beyond said

selectively angled remote straight line focus in the plane of the directrix and on the major axis of the generating ellipse.

14. A light reflector comprising a warped surface having a proximate focal point and a remote focal straight line spaced apart in a directrix plane, a conic section curve as a directrix in said plane having a focus coincident with said proximate focal point, said warped surface being formed to include a series of generating ellipses of varying size, each lying in a plane perpendicular to the directrix plane and extending along the path of a focal ray of the directrix, said generating ellipses each being a vertical section of an ellipsoid by its associated perpendicular plane through its remote focus, said ellipsoid having a point in its surface which is coincident with the directrix at the point of intersection of the directrix with said associated perpendicular plane, said ellipsoid having its proximate focus coinciding with said focal point and its remote focus coinciding with the point of intersection of said remote straight focal line with said associated perpendicular plane.

15. The structure of claim 14, and wherein the remote apex of each generating ellipse is located beyond the said remote straight focal line and in the directrix plane at the point of intersection of said ellipsoid and the major axis of said generating ellipse.

16. The structure of claim 14, and wherein the remote apices of the series of generating ellipses form the rear boundary edge, in the plane of the directrix, of said reflector.

17. A light reflector comprising a warped surface having a proximate focal point and a remote focal straight line spaced apart in a directrix plane, a conic section curve as a directrix in said plane having a focus coincident with said proximate focal point and a principal axis, said warped surface being formed to include a series

of generating ellipses of varying size, each lying in a plane vertical to the directrix plane, said generating ellipses each having a vertex lying in the directrix curve and a remote focus lying in said remote focal line, the proximate focus of each generating ellipse falling within the directrix curve and in the directrix plane a distance equal to the distance between its remote focus and its remote apex, and wherein said remote focal straight line lies in said directrix plane inclined at an oblique angle to said principal axis of the directrix curve.

18. A light reflector comprising a warped surface having a proximate focal point and a remote focal straight line spaced apart in a directrix plane, a conic curve section as a directrix in said plane having a focus coincident with said proximate focal point and a principal axis, said warped surface being formed to include a series of generating ellipses of varying size, each lying in a plane vertical to the directrix plane, said generating ellipses each having a vertex lying in the directrix curve and a remote focus lying in said remote focal line, the proximate focus of each generating ellipse falling within the directrix curve and in the directrix plane a distance equal to the distance between its remote focus and its remote apex, and wherein said generating ellipses all converge to include a common point in said directrix plane.
